UNITED STATES PATENT OFFICE.

HENRY C. WEEDEN, OF BOSTON, MASSACHUSETTS, ASSIGNOR TO THE WEEDEN SANITARY MANUFACTURING COMPANY, OF RHODE ISLAND.

WATER-CLOSET BOWL.

SPECIFICATION forming part of Letters Patent No. 416,139, dated November 26, 1889.

Application filed April 15, 1889. Serial No. 307,256. (No model.)

To all whom it may concern:

Be it known that I, HENRY C. WEEDEN, of Boston, in the county of Suffolk and State of Massachusetts, a citizen of the United States, have invented certain new and useful Improvements in Water-Closet Bowls, of which the following is a specification.

The object of my invention is to produce an improvement in the construction of the seats of water-closet bowls, whereby they will be better adapted to meet certain demands of the public, and I have represented it in the accompanying drawings as embodied in a convenient form.

15 In the drawings, Figure 1 is a view in vertical section of a closet-bowl embodying my present improvement, and Fig. 2 a plan view of the same structure, but with the seat removed.

20 As is well known, it has heretofore been the custom to provide, in connection with water-closet bowls, a perforated seat placed above the bowl and usually hinged to and supported upon the wooden frame-work or 25 casing with which the bowl is surrounded. Of late years, however, it has been deemed desirable to dispense with a surrounding wooden casing and to allow the wooden seat to rest upon the top of the bowl itself. Several objections exist in practice to the use of 30 a wooden seat, particularly a hinged one. For example, when used in connection with an earthenware bowl, such as is now generally used, the wooden seat is likely to be dropped accidentally upon the bowl, thereby 35 breaking or marring it. Furthermore, in the case of invalids, particularly women, the unyielding character of the wooden seat has been found to be injurious. To remedy these 40 defects is the particular object of my present invention.

I will now describe my invention as applied to a closet-bowl of the earthenware wash-out class, that form of bowl being now in extensive use.

45 In applying my invention I dispense entirely with a hinged or folding seat and form the supporting part of the seat by adding to the upper part of the bowl within the rim A 50 thereof a shelf, as shown at B. This shelf preferably corresponds in its interior contour with the contour of the bowl when an ellip-

tical-top bowl, as shown in the drawings, is used. If, however, a square-top bowl were used, such as are now upon the market to a limited extent, the shelf would obviously be of square form to correspond with the top of the bowl, but its interior contour would still be elliptical, that being the customary shape. In the case of an earthenware bowl, as shown, the shelf is preferably made of earthenware and integral with the bowl.

The shelf B, as is obvious, would of itself serve as a seat, but would still possess the disadvantage of being hard and unyielding. To overcome this I provide, in connection with the shelf B, a superimposed yielding seat or cushion, as shown, adapted to rest upon and be supported by the shelf B, this last-named seat or cushion being made, as stated, flexible or soft, fitting the device for use by invalids and in other cases where a seat of hard material would be objectionable.

To secure the flexible seat in place upon the shelf B, I preferably form a flange or groove in the shelf, as shown at C, and provide upon the under surface of the flexible seat or cushion a tongue adapted to enter the groove, thus holding the seat in place upon the shelf. A convenient form for the groove and tongue is represented at Fig. 1, one wall of the groove being made overhanging, so as to insure a tighter clinging of the flexible pad in place upon the shelf.

I am aware that a rubber packing has heretofore been inserted between the top of the closet-bowl and the under side of the seat to form a gas-tight joint. It will be observed, however, that such a device is quite distinct from my invention, an important feature of which is the flexible or yielding seat surface as distinct from one made of non-flexible material with the advantages set forth.

I claim—

1. The combination, with a water-closet bowl, of a seat-supporting shelf connected to the inside of the rim of the bowl, and a seat or cushion of flexible material adapted to rest upon and be supported by the said shelf, substantially as and for the purpose set forth.

2. In combination, a water-closet bowl, a seat-supporting shelf B, located within the rim of the bowl at its upper part, and a seat or cushion of flexible material, the said shelf

and seat being connected by a tongue-and-groove connection, as set forth, whereby the seat is held in place upon the shelf.

3. In combination, with a water-closet bowl,
5 a shelf B, connected thereto at the upper part
of the bowl and within the rim thereof, a
groove in the upper side of said shelf, a seat
or cushion of flexible material adapted to
rest upon and be supported by the said shelf
10 and having a flange or tongue formed on its
under side and adapted to enter the groove

in the upper face of the shelf, whereby the
said flexible seat is held in place upon the
shelf, substantially as set forth.

In testimony whereof I have hereunto sub- 15
scribed my name this 1st day of April, A. D.
1889.

HENRY C. WEEDEN.
